Dr. J. H. Huddard
his ATTORNEY.

UNITED STATES PATENT OFFICE

2,116,999

REFRIGERATION

Carl T. Ashby, Evansville, Ind., assignor to Servel, Inc., New York, N. Y., a corporation of Delaware

Application January 7, 1936, Serial No. 57,877

6 Claims. (Cl. 261—119)

My invention relates to refrigeration and more particularly to an improved absorber or evaporator construction for an absorption refrigeration system of the inert gas pressure equalized type as disclosed in U. S. Patent No. 1,609,334 to von Platen and Munters.

In evaporators and absorbers for this type of system various methods have been used for increasing the effectiveness of gas and liquid contact, such as providing mesh within the tube, or providing discs or dams to increase the surface covered by the liquid. The object of the present invention is to provide a very simple, inexpensive, and more effective construction to produce this result.

Further objects and advantages will become apparent from the following description taken in conjunction with the accompanying drawing, in which:

20 Fig. 1 is a diagrammatic showing of a heat exchanger in accordance with the invention; and

Fig. 2 is a cross-sectional view of the tube forming the heat exchanger of Fig. 1.

Referring to Fig. 1, the heat exchanger which 25 may be either an absorber or an evaporator comprises a coil having a number of inclined straight portions 10 and bent portions 11, and an inlet 12 at its upper end for entrance of absorption liquid, refrigerant, or other liquid. The exchanger 30 is mounted in a vertical plane to permit flow of liquid therethrough by gravity. The exchanger may, for example, be made up of a number of straight metal tubes having a bend at one end, the straight end of each tube being welded to the 35 bent end of the next to form the construction shown. In each of the tubes is positioned a metal rod 13, preferably rounded, which is welded at its ends or along its length to the tube so that upon assembly of the heat exchanger the rod lies closely against the inner wall of the tube at the bent portion and the upper wall of the tube along the 40 length of the inclined straight portion.

The liquid flows in the presence of a gas which 45 may be introduced at 14 into the upper end of the coil, or at 15 into the lower end of the coil. When the coil is employed as an absorber in an absorption refrigeration system of the type referred to above and absorption liquid enters through inlet 12, a gas mixture of refrigerant and inert gas is 50 introduced into the lower end of the coil at 15. When the coil is employed as an evaporator in such an absorption refrigeration system and liquid refrigerant enters through inlet 12, inert gas may be introduced into the upper end of the coil 55 at 14.

In operation, liquid enters the device through the inlet 12 and flows along the bottom of the tube and in the presence of a gas. As it flows around the bend it is drawn into the angle formed by the walls of the rod 13 and the tube. Liquid 5 is held in the angular space by capillarity. After it passes the bend, most of the liquid flows down over the walls of the tube in a constantly moving thin layer having a large surface. Some of the liquid will also form a film on the rod and 10 drip from the rod.

Various modifications may be made within the spirit and scope of the invention as indicated in the following claims.

What I claim is:

1. Gas and liquid contact apparatus for refrigeration apparatus including a coil having inclined straight portions and bent portions, structure for introducing gas and liquid into said coil for flow thereof in the presence of each other, 20 and capillary means within the coil secured to the inner wall of said coil at each of said bent portions and to the upper wall of the straight portion immediately therebelow.

2. Gas and liquid contact apparatus for refrigeration apparatus including a coil having inclined straight portions and bent portions, structure for introducing gas and liquid into said coil for flow thereof in the presence of each other, and a plurality of rods within the coil, each of said 30 rods contacting the inner wall of said coil at one of said bent portions and the upper wall of the straight portion immediately therebelow.

3. A heat exchange device including a tube inclined from a vertical plane, structure for introducing gas and liquid into said tube for flow thereof in the presence of each other, and a smaller circular member extending lengthwise within said tube and secured to the upper wall part of 40 the tube.

4. A heat exchange device including a tube inclined from a vertical plane, structure for introducing gas and liquid into said tube for flow thereof in the presence of each other, and a smaller member extending lengthwise within and secured against the upper wall part of the tube, said member being curved in section and forming angular spaces with the upper wall part of said tube for holding liquid by capillarity.

5. A heat exchange device including a tube somewhat inclined to the horizontal, structure for introducing gas and liquid into said tube for flow thereof in the presence of each other, and a smaller member extending in the direction of its length 55

within said tube and attached to the ceiling thereof.

6. A heat exchange device including a tube somewhat inclined to the horizontal, structure for introducing gas and liquid into said tube for flow thereof in the presence of each other, and a

smaller member extending in the direction of its length within said tube and attached to the ceiling thereof to form a catching device with the tube for guiding liquid into the crevices formed between the tube and said smaller member.

CARL T. ASHBY.
